DESIGN FOR A CONDIMENT DISPENSER CAP

Valentine Schindelbeck, Boonton, N. J.

Application March 9, 1940, Serial No. 90,783

Term of patent 14 years

To all whom it may concern:

Be it known that I, Valentine Schindelbeck, a citizen of the United States and resident of Boonton, in the county of Morris, in the State of New Jersey, have invented a new, original, and ornamental Design for a Condiment Dispenser Cap, of which the following is a specification, reference being had to the accompanying drawing, forming a part thereof.

Figure 1 is a front elevational view of a condiment dispenser cap; Figure 2 is a side elevational view of the same; Figure 3 is a rear elevational view of the same; and Figure 4 is a top plan view of the same, showing my design.

I claim:

The ornamental design for a condiment dispenser cap, as shown.

VALENTINE SCHINDELBECK.
